UNITED STATES PATENT OFFICE.

HERMAN FLEISCHER, OF NEW BRITAIN, CONNECTICUT, ASSIGNOR TO THE STANLEY WORKS, OF NEW BRITAIN, CONNECTICUT, A CORPORATION OF CONNECTICUT.

BUTT, HINGE, AND THE LIKE.

1,076,968.

Specification of Letters Patent.

Patented Oct. 28, 1913.

Application filed March 24, 1913. Serial No. 756,287.

To all whom it may concern:

Be it known that I, HERMAN FLEISCHER, a citizen of the United States, and a resident of New Britain, in the county of Hartford, and State of Connecticut, have invented certain new and useful Improvements in Butts, Hinges, and the like, of which the following is a specification.

The object of the invention is to provide a lubricant for the butt pin upon which the leaves swing, in order to insure an easy-moving device, and to eliminate wear.

The invention is illustrated in the drawings in which—

Figure 1 is a view of a butt in which my invention is embodied. Fig. 2 is a view of the butt-pin.

Referring to the drawings, *a*, *b*, denote the leaves of the butt, *c*, *d*, the knuckles, *e*, the pin annularly grooved as at *f*, at points coincident with the joints between the knuckles, the groove being sufficiently wide

to extend into the end of each knuckle. This groove is packed with a lubricant of suitable character, providing a continuing source of supply, which is wiped into the bearing and insures the easier working of the butt and eliminates any tendency to wear which would be present in case the leaves were working on a dry bearing.

I claim as my invention:

In a device of the character described the combination with the leaves provided with coöperatively arranged knuckles, of a pin extending longitudinally through said knuckles to secure said leaves together, and an annular lubricant-holding channel formed in and as a part of said pin at a point coincident with one or more of the joints between adjacent knuckles.

HERMAN FLEISCHER.
